CLAIM

The ornamental design for a medical infusion adapter, as shown.

DESCRIPTION

FIG. 1 is a perspective view of a medical infusion adapter showing our new design including covers over the fluid ports and spike of the adapter;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a perspective view of the medical infusion adapter of FIG. 1 without the covers for ease of illustration and with portions of the fluid ports and the spike shown in dashed lines;

FIG. 9 is a front elevation view thereof;

FIG. 10 is a rear elevation view thereof;

FIG. 11 is a top plan view thereof;

FIG. 12 is a bottom plan view thereof;

FIG. 13 is a right side elevation view thereof; and,

FIG. 14 is a left side elevation view thereof.

Portions of the medical infusion adapter shown in dashed lines in FIGS. 1, 4, and 6-14 depict unclaimed portions of the medical infusion adapter that are included for environmental purposes only.
